(57) **CLAIM**

The ornamental design for an angled gun grip, as shown and described.

DESCRIPTION

FIG. 1 is a front perspective view of a new design for an angled gun grip.

FIG. 2 is a perspective view of the angled gun grip of FIG. 1.

FIG. 3 is a front view of the angled gun grip of FIG. 1.

FIG. 4 is a rear view of the angled gun grip of FIG. 1.

FIG. 5 is a left side view of angled gun grip of FIG. 1.

FIG. 6 is a right side view of the angled gun grip of FIG. 1

FIG. 7 is a top view of the angled gun grip of FIG. 1; and, FIG. 8 is a bottom view of the angled gun grip of FIG. 1. The broken lines and areas within them in the drawings depict portions of the angled gun grip that form no part of the claimed design.

1 Claim, 8 Drawing Sheets
